UNITED STATES PATENT OFFICE

2,529,163

SHOE POLISHING KIT

Frank W. Knight, Somerville, Mass.

Application November 28, 1944, Serial No. 565,485

1 Claim. (Cl. 15—258)

1

It is one object of this invention to provide a shoe treating kit wherein a flexible, polishing tongue cooperates with a transverse wrapper to form a compact package, including a container for shoe dressing and a dauber adapted to be used in connection with the contents of the container.

A mechanic who abides by what is claimed may make such changes as his skill may direct, without departing from the spirit of the invention.

In the drawings:

Figure 1 shows, in perspective, a device constructed in accordance with the invention, the device being opened.

Figure 2 is a perspective view wherein the device is shown folded.

Figure 3 is a perspective view wherein the device is shown partially folded.

The shoe treating kit forming the subject matter of this application comprises a flexible, elongated, polishing tongue 1, folded along a longitudinal line, as indicated at 2, intermediate its lateral edges 3, to define an outer wall 4 and an inner wall 5. The lateral edges 3 of the walls 4 and 5 are free.

A transverse, free ended, flexible wrapper 6 is secured near one of its longitudinal edges, as shown at 7 to one end portion of the outer wall 4, the corresponding end portion 8 of the inner wall 5 being free from the wrapper 6, whereby the tongue 1 may be opened transversely to afford an area equal to the combined areas of the inner wall 5 and the outer wall 4.

A container 9 for shoe dressing is superposed on the inner wall 5 of the tongue 1, preferably at the free end of the tongue. A thin, flexible dauber 10, for use in connection with the contents of the container 9, is mounted removably between the walls 4 and 5 and tongue 1, underneath the container 9.

The folded tongue 1 is wound about the container 9, to form an open ended enclosure 11 for the container 9, and for the dauber 10. The wrapper 6 is long enough so that its end portions constitute flaps 12, adapted to be connected by snap fasteners 14, or otherwise, the wrapper being engaged about the enclosure 11, across the open ends thereof and across oppositely disposed portions of the container 9.

The tongue 1 exercises a two-fold office, in that it serves as a polishing element and serves also as a part of the means which retains the

2

container 9 and the dauber 10. Any materials of construction may be employed. The dauber 10 may be a thin piece of felt, or a piece of cloth; the tongue 1 may be a piece of cloth suitable for polishing surfaces, and the wrapper 6 may be made of leather or a leather imitation or substitute, or anything else. The container 9 is not fastened to the tongue 1.

What is claimed:

- 10 A shoe treating kit comprising an elongated flexible polishing tongue folded upon itself along its longitudinal center line to define an outer wall and an inner wall overlying said outer wall, a short free-ended flexible wrapper stitched intermediate its ends along one of its longitudinal edges to one end of the outer wall and having its ends projecting laterally beyond the tongue to define laterally projected cover flaps, the other longitudinal edge of the wrapper being disposed beyond said end of the outer wall, the corresponding end portion of the inner wall being free from the wrapper to permit unfolding of the tongue to its original area, the folds of the tongue providing a pocket to receive an article therebetween, 15 said tongue adapted to be folded upon itself along lines disposed perpendicular to its longitudinal center line to partially enclose said article, and said flaps adapted to be extended around the folded tongue to completely enclose said article and prevent unfolding of the tongue.
